UNITED STATES PATENT OFFICE.

JOHN P. WINTERS AND MELVIN McCAMON, OF ELDORADO, KANSAS.

FILTER.

1,366,143.

Specification of Letters Patent. Patented Jan. 18, 1921.

Application filed April 23, 1920. Serial No. 376,035.

To all whom it may concern:

Be it known that we, JOHN P. WINTERS and MELVIN McCAMON, citizens of the United States, residing at Eldorado, in the county of Butler, State of Kansas, have invented a new and useful Filter, of which the following is a specification.

This invention relates to a filter particularly designed for use in separating the lighter and heavier portions of mineral oils and more especially for removing oil from the heavy precipitates or basic settling better known as "B. S." which accumulate on the bottoms of tanks where oil is stored.

15 A further object is to provide a filter of this character which is simple, durable and efficient and will operate continuously, it being possible to install the filter in tanks of different sizes.

20 With the foregoing and other objects in view, which will appear as the description proceeds, the invention resides in the combination and arrangement of parts and in the details of construction hereinafter described 25 and claimed, it being understood that, within the scope of what is claimed, changes in the precise embodiment of the invention shown can be made without departing from the spirit of the invention.

30 In the accompanying drawing, which is a section through a filter embodying the present improvement, the preferred form of the invention has been shown.

Referring to the drawing by characters 35 of reference, 1 designates a tank of any desired proportions provided upon the bottom thereof with a central supporting frame 2 from which extends an upwardly projecting pipe 3 opening through the top 4 of the tank. 40 The mineral oil is adapted to be supplied to this pipe 3 through a feed pipe 5. Radiating from the structure 2 and within the tank are upwardly diverging beams 6 supporting a conical container 7 preferably formed of 45 sheet metal and the lowermost portion of which is preferably filled with concrete as shown at 8 so as to hold the parts properly spaced and anchored relative to each other. The container 7 is spaced from the wall 50 of the tank as indicated at 9 and supported above the container are transverse beams 10 on which is erected a foraminous partition 11. Filtering material such as excelsior and 55 which has been shown at 12, is mounted on the foraminous bottom 11 and is covered with a foraminous top 13.

Outlet pipes 14 are extended from the bottom portion of the container 7 and through the wall of the tank and have valves 15. Additional outlet pipes 16 are extended 60 through the wall of the tank 1 at points just below the upper edge of the container 7 and are also provided with valves 17. Another outlet pipe 18 is extended from the upper portion of the tank for the purpose of carrying off the refined or filtered oil.

In using the apparatus the mineral oil is supplied to the tank through the pipe 3 and spreads out in the bottom portion of the tank. The lower portion of the tank 1 contains water which extends to the level of the pipes 16 and surrounds the conical container 7. The mineral oil when discharged into the lower portion of the tank 1 will rise through the water and will overflow into the container 7 which constitutes a settling compartment. Here the basic settling will be separated from the remainder of the oil which remainder will arise through the foraminous partition 11 and the filtering material 12 and will flow outwardly by way of the pipe 18. The basic settling can be withdrawn through the pipes 14 by opening the valves 15 and the water can be drawn off whenever desired by opening the valves 17 85 and the pipes 16.

What is claimed is:

A filter including a tank, a supply pipe extending downwardly thereinto, a conical container within the tank and concentric 90 with the pipe, said pipe opening into the space below the container, the container being spaced at its margin from the wall of the tank and having its small end lowermost and closed at its center about the pipe, means 95 for drawing off the contents of the container, means below the upper edge of the container for maintaining water in the lower portion of the tank at a predetermined level, a filtering material supported above the container, and means for drawing off the filtered liquid at a point above the filtering material.

In testimony that we claim the foregoing as our own, we have hereto affixed our signatures in the presence of two witnesses.

JOHN P. WINTERS.
MELVIN McCAMON.
